UNITED STATES PATENT OFFICE.

WALTER W. WILLIAMS, OF BLOOMINGTON, ILLINOIS.

LIQUID-FUEL-ATOMIZING DEVICE.

Application filed August 4, 1920. Serial No. 401,148.

To all whom it may concern:

Be it known that I, WALTER W. WILLIAMS, a citizen of the United States of America, residing at Bloomington, in the county of McLean and State of Illinois, have invented certain new and useful Improvements in Liquid-Fuel-Atomizing Devices, of which the following is a specification.

My invention relates to liquid fuel atomizers for heating purposes in conjunction with the ordinary furnace, being used either alternately therewith or independently thereof.

The object of this invention is to produce a liquid fuel atomizer, burning any fuel oil, and capable of practical use either in conjunction with the ordinary house furnace or with larger heating plants.

Another object of the invention is to provide an improved means for mixing the air and oil, which results in a complete atomization thereof.

Yet another object is to provide special valve mechanism for automatically starting and stopping the device, and for regulating the operation of the fuel feed.

A further object is in the provision of a single means for taking the air and oil, thoroughly mixed and under pressure, to the burner.

A still further object of the invention is to provide a by-pass for the diversion of excess air from the mixture expelled from the rotary pressure pump, thereby reducing in great part the roaring noise so common in oil burners.

Further objects will hereinafter appear.

The invention consists of the parts and the construction and combination of parts as hereinafter more fully described and claimed, in which:

Fig. 1 is a perspective view of the liquid fuel atomizer;

Fig. 2 is a sectional view on the line 2—2 of Fig. 1;

Fig. 3 is a sectional view on the line 3—3 of Fig. 1;

Fig. 4 is a cross-sectional view on the line 4—4 of Fig. 3;

Fig. 5 is a perspective view of the jet, showing the manner of mounting the jet in the furnace.

Fig. 6 is an enlarged sectional view of the jet.

Referring to the drawings in detail, A

indicates an electric motor mounted on a base B, and C a rotary pressure pump, the shaft of the motor furnishing the axis of the pump designated as 1. A rotator 2 is eccentrically mounted on the axis and rotates within a cylinder 3 having airtight ends 4. The rotator has three longitudinal slots, indicated at 5, said slots being parallel to the axis and running the full length of the rotator. In these slots are laminated vanes 6, slidable therein and acting as a seal under the influence of centrifugal force when the pump is rotating.

A packing gland is mounted between the motor and pump, said gland consisting of 70 a flange bushing 6^a, mounted upon the pump axis or shaft, rotating with it. It is so placed that the pressure of the pump presses it outward against a leather or fibre washer 6^b, preventing oil and air from escaping 75 from the pump.

When the motor is started and the pump rotated, a pressure is raised therein, which is communicated through connections 7 and 8 to the rear of diaphragms within the 80 primer and pressure valves 9 and 10 respectively, said pressure being registered on the pressure gauge 11. The pressure against the rear of the diaphragm within the valve 9 acts on a valve mechanism, within a valve 85 casing 9^a, similar to that shown in Fig. 2 of the drawings, descriptive of the pressure valve mechanism, and a pressure is communicated through the piping 12 to a tank 13 containing a priming fluid, said fluid 90 being taken into the tank from a container 14 through a connection 15 having a ball check valve 16 therein. The pressure exerted in the priming tank forces the priming fluid, kerosene being the usual primer, 95 through the piping 17 and the safety ball check valve 18 to the rotary pressure pump C.

At the same time that pressure is acting on the primer mechanism, a similar pressure 100 is exerted against the rear of the diaphragm 19 in pressure valve 10, pressing inwardly an oil flow adjustment valve 21 on the rod 20, forcing said valve from its seat 22 to a position midway, or approximately so, between valve seats 22 and 23. The position of the oil flow valve is determined both by the pressure exerted on the diaphragm 19 and the tension of the spring 24, regulated by the adjusting nut 25 and connecting 110

means 26. The action of the valve mechanisms may be regulated to begin when a certain pressure has been raised. An oil intake pipe is designated at 27, coming from a fuel oil container, not shown.

When the diaphragm has been forced inwardly by pressure against its rear face, the oil coming in from the intake pipe passes around the oil adjustment valve and into 10 the pressure valve 10, thence past the outlet 28 and through the pipe 29 to the rotary pump C. Just before the entrance of either the priming fluid or the fuel oil into the pump, they are mixed with air from an inlet pipe 30. The above along with the mixture 15 of the air and oil that takes place within the pump, produces practically a complete atomization.

The mixture is admitted ahead of one of 20 the laminated veins when the rotator is in such a position that the vein is extended; hence, the further movement of the rotator due to its eccentric mounting within the cylinder places the fuel mixture under pressure and forces it out of the pump through 25 the pipe 31 to the burner, later described.

As it has been found that an unrestricted amount of air mixed with fuel and placed under great pressure produces a loud roaring noise when the burner is in action, a 30 by-pass designated at 32 has been constructed to carry the excess air in the mixture back to its original entrance to the pump. An adjustment valve 33 is used to regulate 35 the amount of air to be taken back.

The fuel mixture under pressure from the pump passes through the pipe 31 and then through a special jet designated at 34. This jet, as shown in Fig. 6 of the drawings, has 40 a helix 35 mounted therein, said helix having radially mounted grooves 37 thereon, and cones 36 projecting from either end; said radial grooves and cones giving the mixture that passes therethrough a whirling action. 45 The nozzle of the jet opens at a slight angle 38 and in conjunction with the whirling action set up by the helix and cones, the mixture comes out in a fine whirling vapor.

The fuel penetrates the furnace D and 50 the jet projects into a cylindrical chamber or burner designated as 39, in such a manner that the jet is set at an angle with the inner wall of the burner, the spray from the jet being so directed that it travels approximately parallel to the inner wall thereof, causing the flame to travel about the surface of the chamber. It may be said here that the burner above described is referred to 55 with relation to burners or combustion chambers as used in oil burning outfits as distinguished from the chambers, we will say, in internal combustion engines, wherein a mixture is exploded. A draft means for the burner is shown at 40. A pilot light, 60 not shown, is situated within the furnace

and just beneath the nozzle of the jet. This light furnishes the ignition means for the fuel mixture.

For a more complete understanding of the action of the atomizer, its operation is re- 70 cited:

The electric motor which operates the atomizing device is started either by the action of a thermostat or by the throwing of an ordinary switch in connection therewith. 75

The action of the electric motor rotates the pressure pump and the pump produces a pressure that is transmitted to the diaphragms in the pressure valves, both primer 80 valve and pressure valve; the pressure on the primer valve diaphragm acts on the valve mechanism therein and transmits pressure to the priming tank, wherein a flow of priming fluid is forced to the rotary 85 pump. This special priming mechanism makes possible an immediate ignition of the fuel mixture from the pilot light, by greatly enriching the mixture, the ordinary fuel oils not being readily ignited at low 90 temperatures. The primer valve mechanism is regulated to act but temporarily, or rather coincident with the starting of the device, and ceases automatically when a high 95 temperature has been raised and the ordinary fuel mixture is readily ignitable.

Coincident with the priming valve action is the working of the oil flow adjustment valve. The pressure raised by the pump is communicated to the rear of the diaphragm 100 in the pressure valve and the oil flow adjustment valve is forced from its seat 22 to an intermediate position, thereby permitting the fuel oil, formerly checked, to flow through the valve and by piping to the rotary pump. The tension of the valve is determined by a screw and spring means and hence the flow may be regulated to produce 105 the fuel mixture that is desirable.

The oil flow is automatically maintained 110 due to the pressure valve mechanism. An increasing amount of oil entering the pump causes an increased pressure therein, therefore, an increased pressure on the pressure valve and a consequent reduction in the oil 115 flow due to the movement of the oil flow adjustment valve between its seats. Also, a decrease in the amount of oil entering the pump produces a decrease in pressure, a consequent shifting of the adjustment valve, 120 and an increased oil flow. Should this valve become clogged by heavy fuel or dirt, the pressure in the pump immediately falls, thus allowing the valve to open wider, permitting the obstruction to pass through, not 125 impairing the operation of the device.

Both the priming fluid and the fuel oil are mixed with air just before their entrance into the pump and are almost completely atomized within the pump, also they 130

are placed under great pressure due to the eccentric mounting of said pump. The fuel mixture is taken from the pump under pressure through a single tube to the burner, an excess of air in the mixture being taken off, however, by a by-pass; this relief of the excess air pressure resulting in a comparatively quiet burner. The fuel mixture is expelled from the device through a special jet into a cylindrical chamber or burner in a fine whirling vapor that follows a path approximately parallel to the inner wall of the chamber.

As has been stated, the operation of the machine is automatic and a cessation of the motor and pump produces immediate loss of pressure, thereby a closing of the valve on its seat, resulting in a checking of the oil flow and stopping of the action of the atomizer.

What I claim is:

1. In an oil burning device, the combination comprising, a rotary pressure pump for atomizing fuel mixture, an electric motor for operating said pressure pump, a burner, automatic valve mechanism for regulating the fuel flow to the pump, said mechanism controlled by the pressure raised within the pressure pump, and a single tube for transmitting the fuel mixture under pressure from said pump to the burner.

2. In an oil burning device, the combination comprising a rotary pressure pump for atomizing a fuel mixture, power means for operating said pump, a fuel supply tube for the pump, automatic valve mechanism for regulating the fuel flow to the pump, said mechanism controlled by the pressure raised within said pump, and means for taking the fuel mixture, under pressure, from the pump.

3. In an oil burning device, the combination comprising, a chamber including a rotating member therein for atomizing a fuel mixture, automatic valve mechanism for regulating the fuel flow to the atomizing chamber, said mechanism controlled by the pressure raised within said chamber, and means for taking the fuel mixture, under pressure, from the atomizing chamber.

4. In an oil burning device, the combination comprising a rotary pressure pump for atomizing a fuel mixture, power means for operating said pump, a burner, automatic valve mechanism for regulating the fuel flow to the pump, means for supplying air to the said pressure pump, and means for transmitting the fuel mixture, under pressure, from the pump to the burner.

5. In an oil burning device, the combination comprising a rotary pressure pump for atomizing a fuel mixture, automatic primer valve mechanism, said mechanism acting upon the initial movement of the device, automatic pressure valve mechanism controlling the supply of fuel to the pump, means

for supplying air to the said pressure pump, and means consisting of a single tube for transmitting the fuel mixture, under pressure, from the pump.

6. In an oil burning device, the combination comprising air and oil supply means, a burner, and means interposed between the air and oil supply means and the burner and communicating therewith, respectively, for receiving air and oil and for reducing the volume thereof, under compression, preliminary to discharge to the burner.

7. In an oil burning device, the combination comprising a compressor chamber, means for admitting air and oil thereto, a burner spaced from said chamber, means within said chamber for inducing a flow of air and oil thereinto and compressing and mixing said air and oil in said chamber preparatory to discharge to the burner.

8. In an oil burning device, the combination comprising a chamber, means for conducting air and oil thereto, a burner, a rotor within said chamber for inducing a flow of air and oil thereinto preparatory to discharge to the burner, said rotor being constructed to discharge to the burner during each complete revolution the air and oil taken into the chamber during said revolution.

9. In an oil burning device, the combination comprising a compressor chamber, a burner, means within said chamber for inducing a flow of air and oil thereto and compressing same therein, preparatory to discharge to the burner, and a single tube for transmitting the fuel mixture, under pressure, to the burner.

10. In an oil burning device, the combination comprising a rotary pressure chamber, a burner, mechanism within said chamber for inducing a flow of air and oil thereto and compressing same therein, preparatory to discharge to the burner, power means for operating the mechanism within said chamber and means consisting of a single tube for taking the fuel mixture, under pressure, from said chamber.

11. In an oil burning device, the combination comprising a compressor chamber, a fuel supply tube for said chamber, an air intake means in the fuel supply tube, a burner, and means within said chamber for inducing a flow of air and oil thereto and compressing same therein, preparatory to discharge to the burner.

12. In an oil burning device, the combination comprising a chamber, a burner, means within said chamber for inducing a flow of air and oil thereto and compressing same therein, preparatory to discharge to the burner, and automatic valve mechanism for regulating the flow to the chamber, said mechanism being controlled by the pressure raised within said chamber.

13. In an oil burning device, the combination comprising a compressor chamber, a fuel supply tube, air intake means, a burner, and means within the compressor chamber, including a rotor, eccentrically mounted with relation to said compressor chamber, for inducing a flow of air and oil thereto and compressing same therein, preparatory to discharge to the burner.
- 10 14. In an oil burning device, the combination with a rotary pressure pump, of an automatic primer mechanism for supplying priming fluid to the pump upon the initial movement of said pump, an automatic pressure valve mechanism for supplying fuel 15 oil to said pump, said mechanism controlled by the pressure raised within the rotary pressure pump.

In testimony whereof I have affixed my signature.

WALTER W. WILLIAMS.
